UNITED STATES PATENT OFFICE.

FRANCIS W. COOPER, OF MONTREAL, QUEBEC, CANADA, ASSIGNOR, BY MESNE ASSIGNMENTS, TO STEAD RAIL ANCHORS INCORPORATED, OF WILMINGTON, DELAWARE, A CORPORATION OF DELAWARE.

RAIL ANCHOR.

Application filed March 17, 1924. Serial No. 699,645.

This invention relates to improvements in rail anchors of the type shown in Figure 3 of U. S. Patent No. 1,366,558, granted to myself and Henry Steadworthy; and Figure 5 of application Serial No. 623,931, filed the 9th March, 1923, by myself and the said Steadworthy; that is to say, a rail anchor comprising a U-shaped body member notched to embrace one edge of a rail base so as to be supported with the web of the body inclined transversely of the rail and a loop member held in compression between the body web and bottom of the rail base and extending transversely under the rail into engagement with the opposite edge thereof.

In the accompanying drawings which illustrate various but by no means all possible embodiments of the invention:—

Figs. 1, 2, 3, 4 and 7 are side elevations of various modifications of the anchor in position on a rail base.

Figs. 5 and 6 are fragmentary views illustrating further modifications of the anchor.

Referring more particularly to the drawings, 11 designates a rail base and 12 an anchor body of the type shown and described in the patent above mentioned and being a U-shaped member having arms 13 notched at 14 to embrace the edges of a rail base and to be thereby held in such position that the centre web 15 connecting the arms is inclined transversely of the rail and is positioned substantially in its entirety beneath the rail.

Co-operating with the body 12 is a complementary key member or holding member 16 which alone and in combination with the body forms the subject of the present invention. Generally speaking, the holding member is wedge-shaped and is formed of a bar of suitable material such as spring steel bent upon itself toward one end to form a loop 17 at one end of the member, which loop imparts the wedge-shaped appearance and wedging effect to the member. When the member is not in use this loop is preferably open but in course of application the loop is closed or is compressed and by its tendency to open or expand produces the effect hereinafter described. At the opposite end the member is hooked as at 18 for engagement with the edge of a rail base. The member is disposed as shown in various figures of the drawing with the looped end

thereof embraced between the arms of the body member and, when in operation, in compression between the inclined web of the body and the under surface of a rail base, so as to draw downwardly on the body and hold the upper notch-edges thereof in close engagement with the upper surface of the rail base. The compressed looped end of the member tending to expand between the relatively inclined body web 15 and the bottom of the rail base draws the hook 18 and the body into tight engagement with edges of the rail base with clamping effect.

In the form shown in Figure 1, the intermediate or shank portion 19 of the holding member is bent or deflected from a straight line and in operative position is spaced from the rail base intermediate the opposite edges thereof, the form being such that the holding member has a substantial bearing on the bottom of the rail base at what may be termed the junction of the shank and loop which is located between the arms of the body. The tail 20 of the loop when in operative position follows the inclination of the body web and has edge contact with an intermediate portion of the shank. Before application, the deflection of the shank is preferably greater than after application, as may be seen by comparison of the dot and dash lines and full lines in Figure 1; also the looped end is larger before application and the loop tail is preferably spaced away from the shank. When assembled on a rail the looped end is compressed between the body web and rail base to somewhat reduce the size thereof and also to close the same, the action being such that the shank tends to be straightened and the extremity of the loop tail is pressed tightly against the shank usually to such an extent that the tail is slightly flexed downwardly. In this form the upward pressure of the loop tail on the shank causes a substantial bearing on the rail at the junction of the edge or side and bottom thereof, as indicated by the numeral 21. In forming the hook 18 the bar is preferably sheared out of normal to keep the depth of the hook as small as possible for ease of application. The length of the hook is such that it has a very slight bearing upon the upper surface of the rail or only upon the junction of this upper surface with the edge, as indicated at 22. The

only bearing desired is that sufficient to support the hook against being forced downwardly out of engagement with the rail edge by a chance blow.

5 In Figure 2 a holding member similar to Figure 1 is shown having two slight differences. In this form the curvature of the hook is continued under the rail base and a slight offset 23 provided to bear on the 10 under surface of the rail base a short distance inwardly of the edge to replace the bearing at the point 21 shown in Figure 1. With this offset 23 there may be clearance 15 between the rail and the hook at the point 21. The second feature of difference lies in the provision of a longer tail 20 for the loop which will have substantial surface bearing with the shank, preferably at the lowest point thereof, but the looped end 20 will be identical, in form and operation, with the type shown in Figure 1. The form of the holding member before application will be substantially as already described, that is, the deflection will be greater 25 and the loop will be larger.

In Figure 3 there is shown a modification in which the loop is inverted as compared with the forms of Figures 1 and 2; that is to say, the tail of the loop, as well as the 30 looped end, bears against the bottom surface of the rail base, while the shank thereof bears against the web of the body and when applied is flexed from the plane of the web so as to press upwardly against the rail base 35 near the edge opposite from the body. In this form the loop may be open in operation and it will be noted that the shank is curved upwardly toward the rail base instead of downwardly and away from the 40 rail base as in the preceding figures, the flexion being imparted during the application of the holding member which is preferably straight in the shank before application.

45 In Figure 4 a further modification of the type of Figure 1 is illustrated, the shank being offset or reversely curved, as at 24, intermediate the looped and hooked ends to space the shank away from the rail base. 50 The loop tail is preferably bent adjacent its end, as at 25, so as to be in end, abutting relation with the offset and substantially normal to that portion of the shank which it engages. In this modification of the device before application the angular relation of the two parts of the shank on opposite sides of the offset is greater than shown and when the member is applied the shank is flexed between the offset and hook so that 55 the hooked end thereof presses upwardly against the rail base. Further, before application the loop is open as in Figure 1 but on application compression of the loop forces the tail thereof toward the shank 60 end into end abutting relation with the offset

24, so that the loop tail thrusts against the offset in a direction perpendicular to the engaged surface of the offset. While the point of abutment is shown at the lowest point of the shank it may be shifted either 70 way from this point as desired, the perpendicular relation of the tail portion 25 being retained.

In Figure 5 there is shown a holding member end in what may be termed a flattened spiral loop which may replace the corresponding ends of any of the forms previously described, but with the difference that the action of the tail is altered as the tail is in this case turned into the loop. A 75 holding member having this form of end may be disposed either with the shank at the lower side or at the upper side of the loop as desired. Before application the loop is preferably open and is upon application 80 fully closed as shown. The flattening of the loop in manufacture must be sufficient to provide surface bearing upon both anchor body and rail adequate to prevent the holding member end turning or slipping and 85 permitting the hook 18 to move downwardly out of engagement with the rail edge.

The modification shown in Figure 6 is applicable to any of the preceding forms and resides in the provision of a straight 95 portion in the shank adjacent the hook 18 and designated 26, said portion being adapted to obtain surface bearing with the lower surface of a rail base for a short distance inwardly from the edge.

100 In all the forms of anchor thus far described the wedge shape and wedge action have been apparent by reason of the form of the end. In Figure 7 there is shown a modification in which wedge action is obtained similar in effect to that of the previous forms, although the loop is only potential. In this form the hook designated 105 18^a is extended to have substantial bearing on the upper surface of the rail base and the shank 19^a has preferably continuous bearing surface with the bottom of the rail base from the hook to approximately the middle of the base. The shank then curves 110 downwardly away from the base and when in operative position the opposite end or tail 20^a bears on the web of the body. In this form the bearing on the under surface of the rail base replaces the upper part of the loop and the extremity of the shank 115 replaces the bottom of the loop. The wedging effect described in connection with other forms is obtained in this form also but in a different way. In the application of this 120 form the plain extremity of the shank is flexed upwardly and toward the rail base, as will be seen by a comparison of the dot and dash lines and full lines in Figure 7.

125 If desired the form of hook shown in Figure 7 may be applied to the various 130

modifications shown in preceding figures, but in no case is it advisable to have the hook project too far inwardly of the edge of the rail base as it renders the application more difficult and may lead to straining of the holding member.

While in Figures 1 to 4 the notches 14 of the anchor body have been shown of such size that the rail fits snugly between the upper and lower edges of the notches and does not go completely to the bottom thereof, it must be understood that engagement of the notch edges with the lower surface of the rail is not absolutely necessary as the body may be applied, and with good results, to a rail smaller than that for which it was intended. In such a case a small clearance will be found between the notch edges and the under surface of the rail base and the edge of the rail will go completely to the bottoms of the notches, as indicated in Figure 7. It is, however, not advisable that any such clearance should be so great as to permit appreciable tilting of the anchor in the longitudinal direction of the rail when thrusting against a tie, as such tilting tends to unnecessarily, unduly and unequally stress the holding member.

The method of application of the forms of anchor shown in Figures 1 to 6 inclusive is extremely simple. The body is first applied to the rail and the holding member is then passed hooked end first through the body under the rail. When the member has been passed part way under the rail the looped end commences to bind between the upper edge of the body web and the bottom of the rail base, pressing the end of the hook upwardly against the rail base. Force is now applied to the looped end by any suitable instrument, such as a maul, to drive the holding member completely across the rail and at the same time to partially straighten the shank thereof until the hook clears the edge of the rail and snaps up into the operative position shown. During the application the looped end is compressed and closed and the whole length of the holding member tensioned. If desired, as a final step, the hook 18 may be given a slight tap toward the rail to ensure close engagement thereof with the rail at the point 22, but this result is normally obtained by the expansion of the looped end between the converging surfaces of the body web and rail base. In the case of the modifications shown in Figures 1, 2 and 4, compression of the looped end in application forces the tail thereof upwardly and against the shank to partially straighten the same and to hold the hook 18 up in operative position, the effect being due primarily to the inclination of the web 15. In the case of the modification shown in Figure 3 the same result is obtained but by direct co-operation of the

shank 19 and body web. The tendency to expansion in the looped end acts upon the inclined body web and urges the body toward the centre of the rail and at the same time urges the holding member to a withdrawing movement transversely of the rail, which movement is resisted by the hook 18 so that the rail base is resiliently clamped edgewise between the body and holding member hook. This clamping action is so pronounced that great force must be exerted upon the body in the direction of rail length to cause even a slight movement. If such movement does occur in service it results in disposing the holding member out of normal to the rail edges so that the holding member is drawn more tightly between the converging surfaces of the body web and rail base and the looped end further compressed. In this way the grip of the device on a rail increases with the thrust against the body.

In the later stages of the application the holding member shank and loop tail will be flexed to a greater extent than shown in full lines in the drawings. In the forms shown in Figures 1, 2 and 4 the flexion will be such that the shanks are nearly straightened, while in the modification shown in Figure 3 the curvature will be more pronounced than shown. On account of this super-flexion it is desirable to keep the hooks 18 as low as possible to avoid straining the member, but it will be understood that this does not preclude the use of a hook as shown in Figure 7. When a hook of the type shown in Figure 7 is employed the holding member must be driven sufficiently past its final position to clear the tip of the hook from the edge of the rail and after the hook snaps up the holding member must be driven back to relatively enter the rail edge into the hook. The super-flexion of the holding member which necessarily occurs in the application thereof serves to test each member as it is applied, and if the material is soft or flawed the action of the hook 18 will indicate the fact. In the same way if the member is too brittle it will break in application.

The holding member shown in Figure 7 may be applied from either edge of the rail and the hook 18 levered up into proper position. The remarks as to the length of the hook, super-flexion of the member and spring action made in connection with previously described forms apply also to this form. In this case the effect may be said to be attained by tendency of a potential loop to close instead of tendency to open as in other forms. The action of this form of holding member in relation to the rail is the same as with previously described forms.

The anchor may be readily removed in the case of modifications such as shown in

Figures 1 to 4 by a sharp downward blow on the end of the hook to disengage the same from the rail edge. The looped end may then be drawn out through the body and the latter knocked off the rail. With proper dimensions and quality of material the anchor is capable of re-use a number of times. The form of member shown in Figure 7 may best be removed by means of a claw-bar fulcrumed against the head of the rail and used to lever the hook laterally clear of the rail edge. When thus positioned the hook should be struck downwardly until clear of the lower surface of the rail to free the member.

It will be understood that certain structural features of the patent previously mentioned may be used to replace corresponding features of the present disclosure, for example, the form of the hook may, where applicable, be used in place of the hooks herein illustrated and described. Furthermore, the various details herein disclosed may be combined in any manner desired. It will also be understood that the proportions and amount of curvature and flexion herein illustrated are somewhat exaggerated to simplify such illustration, and that the invention is therefore not confined to the proportions, forms and flexions herein shown but that many variations in form, proportion and structural details may be made without departing from the spirit of the invention or the scope of the following claims.

Having thus described my invention, what I claim is:—

1. A rail anchor or the like comprising a body to hook onto one edge of a rail base and a holding member to pass through such body and hookingly engage the edge of a rail base opposite said body, the holding member being formed to engage toward its ends with the under surface of a rail base and to be spaced intermediate its ends from the rail base.

2. A rail anchor or the like comprising a body to hook onto one edge of a rail base and a holding member hooked at one end and presenting at the opposite end an inclined surface to cooperate with wedging action with the body, said holding member being adapted to be passed hooked end first through the body and transversely of a rail into hooking engagement with the rail edge opposite the body, said holding member being formed to engage toward its ends with the under surface of a rail base and to be spaced intermediate its ends from the rail base.

3. A rail anchor or the like comprising a body to hook onto one edge of a rail base and a holding member to hook at one end onto the opposite edge of the rail base and to be compressed at the opposite end between the body and the underside of the rail base,

said holding member being formed to have engagement with the underside of the rail base at or near the opposite edges thereof and to be spaced from the rail base intermediate the edges thereof.

4. A rail anchor or the like comprising a body to hook onto one edge of a rail base and a holding member to be held in compression at one end between the body and the underside of the rail base and at the opposite end to hookingly engage the opposite edge of the rail base, said holding member being offset adjacent its hooked end to bear upon the under surface of a rail base and to space an intermediate portion of the member from the rail.

5. A rail anchor or the like comprising a body to hook onto one edge of a rail base and a holding member to be held in compression at one end between said body and the under surface of the rail base, said member being hooked at its opposite end to engage an edge of the rail base, the hook being formed and dimensioned to have edge engagement with the rail at substantially the junction of the side or edge and top of the base.

6. A rail anchor or the like comprising a body to hook onto one edge of a rail base and a holding member to be held in compression at one end between said body and the under surface of the rail base, said member being hooked at its opposite end to engage an edge of the rail base, the hook being formed to overlie the base only sufficiently to hold the hook against accidental downward disengagement from the base while permitting such downward disengagement by force when desired.

7. A rail anchor or the like comprising a body to hook onto one edge of a rail base and a holding member to be held in compression at one end between said body and the under surface of the rail base, said member being hooked at its opposite end to engage an edge of the rail base, the end of the bar forming the hook being sheared out of normal to the length thereof to reduce the depth of the hook while permitting a slight engagement of the same with the upper surface of the rail base.

8. A rail anchor or the like comprising a body to hook onto one edge of a rail base and a holding member hooked at one end to engage the opposite edge of the rail base and looped at the opposite end to be held in compression between the body and under surface of the rail base, the member being spaced intermediate its ends from the rail base, the looped end of the member having a loop tail spaced from the central part of the member and bent at its end toward the member to have end abutting relation therewith and to stand substantially perpendicular to the surface engaged.

9. A rail anchor or the like comprising

a body to hook onto one edge of a rail base, and a holding member to hook at one end to the opposite edge of the rail base and at the other end to engage the body and formed to engage the under surface of the rail base at a point intermediate its edges, whereby the member is tensioned.

10. A rail anchor or the like comprising a body to hook onto one edge of a rail base and having a seat to be disposed under the rail base, and a holding member including a bent shank, and a loop at one end of the shank adapted for compression between the body seat and a rail base, and a tail on 15 said loop underlying the shank and adapted upon compression of the loop to thrust upwardly against the shank with straightening effect thereon.

11. A rail anchor or the like comprising a body to hook onto one edge of a rail base and having a seat to be disposed under the rail base, and a holding member including a bent shank, and a loop at one end of the shank adapted for compression between the body 25 seat and a rail base, and a tail on said loop underlying the shank and adapted upon compression of the loop to thrust upwardly against the shank with straightening effect thereon, and a hook at the end of the shank 30 opposite said loop adapted to engage an edge of the rail base.

12. A rail anchor or the like comprising a body to hook onto one edge of a rail base and having a seat to be disposed under the rail base and a holding member including a bent shank, a hook at one end thereof for engagement with the edge of the rail base opposite the body, and a wedge-shaped loop at the opposite end of the shank adapted 40 to be forcibly introduced between the body seat and the rail base whereby said loop will be compressed, and a tail on the loop underlying the shank and adapted upon compression of the loop to thrust upwardly against 45 the shank to releasably hold the hook thereof in engagement with the edge of a rail base.

13. A rail anchor or the like comprising a body adapted to hook onto one edge of a rail base and having a seat to be disposed under the rail base, and a holding member including a shank and a wedge-shaped loop at one end thereof adapted to be forcibly introduced between the body seat and the rail base whereby said loop will be compressed and the opposite end of the shank forced upwardly against the rail base with flexion of the shank, and a hook at said opposite end of the shank to engage an edge 55 of the rail base.

14. A rail anchor or the like comprising a body adapted to hook onto one edge of a rail base, and a holding member including a shank reversely bent intermediate its ends 60 whereby said shank will bear adjacent its

ends upon a rail base and will be spaced intermediate such bearings from the rail base, and a loop at one end of the shank adapted to be compressed between the body and rail base and including a tail to thrust upwardly 70 against the intermediate portion of the shank when the loop is compressed, and a hook at the opposite end of the shank from the loop to engage the edge of a rail base.

15. A rail anchor or the like comprising a body to hook onto one edge of a rail base and a key member to enter between the body and a rail base with wedging effect, said key being in its operative position and form flexed between its ends from its form when 80 inoperative, with holding effect, and a hook on the key to engage an edge of a rail base and to be held in such engagement by the tendency of the key to reflex movement to its original form.

16. A rail anchor or the like comprising a body to hook onto one edge of a rail base, and a holding member to hookingly engage the opposite edge of a rail base, said member including a shank and a loop at one end thereof to be compressed between the body and rail base, the loop having a tail turned adjacent its end toward the shank and thrusting against the shank when the loop is compressed.

17. In a two piece rail anchor, a U-shaped member with parallel sides connected by a flat web, inclined slots in the sides adapted to fit on the edge of a rail base, and hold the member with its web inclined towards the under surface of the rail, and a retaining member of strip resilient metal bent to form a wedge, having a long leg bent outwardly in the middle with an outwardly hooked end and a short leg with an inwardly hooked end adapted to bear on the middle of the long leg.

18. In a two piece rail anchor of the type specified, a body member with inclined slots to receive the edge of a rail base, having an inclined surface under the rail and a wedge shaped spring adapted to hold the body member in position on the rail edge, comprising a curved portion, a long leg bent outwardly in the middle with an outwardly hooked end and a short leg with an inwardly hooked end adapted to bear on the middle of the long leg when in compression.

19. In a two piece rail anchor, a body portion with slotted sides adapted to receive the edge of a rail base, an inclined surface therein, a wedge-shaped retaining member adapted to retain the body portion in position on the rail edge, having resilient legs, one of which is bent outwardly and extends to grip the opposite edge of the rail, the other of which extends to the rail axis, slides on the inclined surface of the body portion and compresses the bend of the first leg towards the under surface of the rail.

20. In a two piece rail anchor of the type specified, a wedge shaped spring member having a curved portion, a long leg bent outwardly in the middle and hooked outwardly at the end to grip the edge of the rail base, and a short leg inclined towards the long leg, with an inwardly hooked end adapted to bear on the middle of the long leg and partially flatten the bend thereof, when the wedge shaped spring is under compression.
21. In a rail anchor, a U-shaped body portion notched to embrace one flange of a rail base and a retaining member of strip resilient material bent intermediate its ends to the general form of a wedge and including long and short arms, the long arm being bent intermediate its ends away from the short arm and further outwardly bent adjacent its extremity to provide a hook for engagement with the edge of a rail base flange, and a short arm bent adjacent its end toward the long arm and adapted in service to bear against the long arm with tendency to straightening effect therein.
22. In a rail anchor, a U-shaped body member notched to embrace one flange of a rail base and including a seat portion to be disposed beneath a rail base and inclined transversely thereof, and a holding member for said body being a strip of resilient material bent intermediate its ends to form long and short arms in spaced relation and defining a normally open loop, the long arm of said strip being adapted to engage the under surface of a rail base at opposite edges thereof and being bent intermediate its ends thereby to space it below the central part of a rail base.
23. In a rail anchor, a U-shaped body member notched to embrace one flange of a rail base and including a seat portion to be disposed beneath a rail base and inclined transversely thereof, and a holding member for said body being a strip of resilient material bent intermediate its ends to form long and short arms in spaced relation and defining a normally open loop, the long arm of said strip being adapted to engage the under surface of a rail base at opposite edges thereof and being bent intermediate its ends thereby to space it below the central part of a rail base, the said long arm being formed at its end adjacent the looped end with a substantially straight portion of appreciable length for engagement flatwise with the under surface of a rail base.
24. In a rail anchor, a U-shaped body member notched to embrace one flange of a rail base and including a seat portion to be disposed beneath a rail base and inclined transversely thereof, and a holding member for said body being a strip of resilient material bent intermediate its ends to form long and short arms in spaced relation and defining a normally open loop, the long arm of said strip being adapted to engage the under surface of a rail base at opposite edges thereof and being bent intermediate its ends thereby to space it below the central part of a rail base, and a short arm bent adjacent its free extremity to form a hook turning toward the long arm and adapted to bear against the long arm at about the point of maximum spacing below a rail base upon closure of the loop by compression thereof between the body seat and under side of the rail base.
25. In a rail anchor, a holding member comprising a long arm and a short arm in divergent relation, and a substantially semicircular portion connecting the divergent ends of said arms, a hook at the free extremity of the long arm turned away from the short arm, and a hook at the free extremity of the short arm turned toward the long arm.
26. In a rail anchor, a holding member comprising a long arm and a short arm in divergent relation, a substantially semicircular portion connecting the divergent ends of the arms, the free extremity of the short arm being spaced from the long arm, a hook at the free extremity of the long arm turned away from the short arm, and a hook at the free extremity of the short arm turned toward the long arm.
27. In a rail anchor, a holding member comprising a long arm and a short arm in divergent relation, a substantially semicircular portion connecting the divergent ends of the arms, the long arm being bent intermediate its ends to present a convex surface to the short arm, and a hook at the free extremity of the long arm turned away from the short arm.
28. In a rail anchor, a holding member comprising a long arm and a short arm in divergent relation, a substantially semicircular portion connecting the divergent ends of the arms, the long arm being bent intermediate its ends to present a convex surface to the short arm, a hook at the free extremity of the long arm turned away from the short arm, and a hook at the free extremity of the short arm turned toward the long arm.

In witness whereof, I have hereunto set my hand.

FRANCIS W. COOPER.
